ADJUSTABLE READING AND WRITING TABLE FOR FURNITURE

Filed Nov. 12, 1946

UNITED STATES PATENT OFFICE

2,533,416

ADJUSTABLE READING AND WRITING
TABLE FOR FURNITURE

Lawrence L. Anthes, Toronto, Ontario, Canada

Application November 12, 1946, Serial No. 709,236
In Canada November 16, 1945

6 Claims. (Cl. 311—26)

1

This invention relates to a device for the use of invalids or persons who, while resting in bed or in a comfortable chair, may desire to support reading or writing material in a position which will be comfortable and convenient and which will relieve the person of the stress of holding such material and will form a rest for the arms.

The principal object of the invention is to provide a table which may be easily and quickly adjusted to positions close to the body at an easy and restful angle to permit the person using same to move freely and to provide adjustable means for holding such table in position so that it may be quickly moved clear of the bed or chair.

The principal feature of the invention consists in the novel construction of a board having depending legs on opposite sides adapted to straddle the body of the person to support the board from a bed or chair, the board being movably supported in an inclined position by a flexible cord extending from the upper corners of the table around the frame of the bed or chair.

A further feature of importance consists in providing an adjustable overhead extension from the bed or chair and a flexible suspension means for supporting the table in an inclined position or in a position clear of the person if desired.

In the accompanying drawings Figure 1 is a perspective view of my improved table shown in an operative position upon a bed.

Figure 2 is a small side elevational view showing the application of my improved table to an easy chair.

Figure 3 is an enlarged part plan detail of one side of the board of my improved device.

Figure 4 is an enlarged sectional view through one of the side bars of the frame of the board showing one of the adjustable spring clips thereon.

Figure 5 is an enlarged sectional detail of a portion of the board and side frame showing the detail of a shelf attachment to the board.

The invention as herein illustrated comprises a board 1 formed of a light tough material such as "Masonite" and which is of a width greater than the width of a normal sized person and is formed with a curved bottom edge which terminates in a pair of rounded legs 2, the curved edge and legs being adapted to span a person's body in bed or in a chair so that the legs rest upon the top of the bed or the seat surface of the chair.

The board 1 is preferably provided, as here shown, with tubular top and side edges formed of a length of tubing 3 of thin metal or plastic

2

having a slot 4 cut in its inward side to receive the edge of the board.

Tubular fittings 5 embrace the side portions of the tube 3 adjacent to the top and these are provided with suitable eyes 6 to which the ends of a flexible cord 7 are attached. The loop 8 of this cord is passed around the head end 9 of a bed frame or around the back 10 of a chair and slides in suitable eyes 11 or other guides mounted on the frame or chair. This cord is of such length as to support the upper edge of the board 1 at a suitable angle with the legs 2 resting on the bed or chair straddling the person using it and by shifting the legs the board may be adjusted at different angles from the perpendicular or in transverse relation to the bed or chair. When a transverse adjustment is made the loop of the cord will slip freely through the eyes 11 on the bed or chair frame.

20 The board frame is here shown with light tubular frames 12 arranged at either side. These frames are connected at one end to the top tubular fittings 5 which are adapted to swivel on the side bars and the other ends are connected to the frame sides by similar tubular fittings 13. A suitable thumb screw 14 may be threaded in each of the fittings 13 to secure the side frames in adjusted positions. The frames 12 when turned at right angles to the board 1 form rests to support the table in a horizontal position over the person's body or legs.

25 Mounted on the side members of the frame are spring clips 15 which may be moved to various positions on said sides. Elastic cords 16, or cords in which coil springs 17 are arranged, are connected at one end to the adjustable clips 15 and extend across the board 1 and the other ends are connected to the eyes of the fittings 5. These cross cords may thus be adjusted to overlie the pages of an open book or magazine or other papers placed on the table and such book may be further secured independent of these cross cords by a spring jaw clip 18, the board being provided with a slot opening 19, the edge 30 of which may be gripped along with the book cover by the clip 18.

35 A bed or chair may be provided with a tubular upright 20 arranged centrally of the width thereof and a right angular extension 21 therefrom carries at its outer end a pulley 22.

40 A suitable clip or other fastening member 23 is connected midway of the width of the board 1 at its upper edge and to this is connected a cord 24 which passes over the pulley 22.

45 A pulley 24' is arranged at the juncture of the

3

horizontal extension 21 and the upright and the cord extends thereover and passes downwardly into the upright and is connected to a counterweight 25 which substantially counterbalances the total weight of the board so that if the board is lifted up from its position on the bed the counterweight will retain it in the raised position.

The horizontal angular extension 21 of the tubular upright is here shown telescopic so that the position of the end of the cord depending therefrom may be altered to permit of adjustment of the position of the board 1 relative to the bed end and the person resting therein.

Another feature of my device comprises a shelf 26, the end edges of which are provided with spring clips 27 which will readily spring over the tubular side bars of the frame of the board thus providing a horizontal shelf when the main board surface is arranged in a substantially vertical position. This may be removed or placed in position at will.

It may be found that when this device is applied to a chair the arms may be too close together to permit the legs 2 to rest on the seat surface and in order to permit the table to be used the legs 2 are formed with transversely hinged joints 28 which permit the legs to fold into an angular position to rest upon the chair arms.

Suitable sliding clips 29 are provided on the outer edges of the board 1 which will engage the upper outer edges of the legs to hold them extended and when the legs are to be folded as described it is merely necessary to slide these clips free of the cross hinge joint. The sides of the clips 29 allow a certain flexibility of the joint.

A device such as described has been found to be a great boon to persons compelled to rest in bed or in chairs for long periods as it enables them to read or write or draw with great comfort without straining the arms or back and the table may also be used at meal times by using the side frames as supporting legs.

When the person using the device desires to be free from it he merely lifts it up out of the way where it is held suspended and ready for replacement at any time.

The flexibility of the joints in the legs 2 obviates the transference of vibration to the board when such is used on a moving vehicle and enables the user to write with great comfort.

What I claim as my invention is:

1. A table adapted to be used with an article of furniture, comprising a board having legs extending downwardly at either side, a tubular frame embracing the side and top edges of said board, fittings rotatably mounted on the side members of said frame adjacent to the top and bottom ends thereof, and frames secured to said rotatable fittings and extending substantially parallel with said frame sides.

2. A table adapted to be used with an article of furniture, comprising a board adapted to rest upon the article of furniture and to extend upwardly therefrom, an arm supported by said article of furniture and projecting laterally above

4

said board, a flexible suspension connected between said arm and board to suspend same, a counterbalance connected with said suspension, flexible means connecting the sides of said board with said article of furniture, said flexible suspension and flexible means holding said board to form a supporting surface extending transversely of said article of furniture and permitting and guiding the movement of said board in any direction laterally or vertically of said article of furniture or rotatively relative thereto.

3. A device as claimed in claim 2 in which said

flexible means connecting the sides of said board comprises a flexible cord secured at the ends to opposite sides of the board and passing around and freely slidably relative the back of said article of furniture.

4. A table adapted to be used with an article of furniture comprising a board having legs hinged to the board at either side thereof and adapted to support said board on an article of furniture.

of and adapted to support said board on an article of furniture, clips bridging the hinges connecting said board and legs, said clips having resilient sides engaging opposite faces of said board and legs with said legs extended to form, with said hinges, connections between said board and legs having a flexibility to dampen transfer of vibrations from said legs to said board while returning said legs to an extended position upon displacement therefrom under vibration.

30 displacement therefrom under vibration.

5. A table adapted to be used with an article of furniture comprising a board having legs hinged thereto at either side thereof and adapted to be tilted to an angle of from

ed to support said board on an article of furniture, clips normally engaging said board and legs 35 and bridging the hinge connection therebetween and having sides engaging opposite faces of said

and having sides engaging opposite faces of said board and legs with said legs extended resiliently resisting movement of said legs from an extended position while permitting such movement under impact to dampen transfer of vibrations from said legs to said board and acting to return said legs to the extended position upon displacement therefrom.

45 6. A device as claimed in claim 5 in which said
lips are pivoted to said board and are movable
from a position bridging said hinge connections
to a position clear of said hinges to permit said
legs to be swung from an extended position.
